CIGARETTE TURNING DEVICE

John T. Dalton, Durham, N. C., assignor to The American Tobacco Company, New York, N. Y., a corporation of New Jersey

Application November 2, 1948, Serial No. 57,927

4 Claims.

(Cl. 198—33)

This invention relates to the manufacture of cigarettes and more particularly to improvements in cigarette making machines employed in the manufacture of tipped cigarettes.

In the manufacture of cigarettes, tobacco is delivered in uniform amounts from a tobacco feeder to a cigarette making machine. The tobacco so fed is passed through a tubular member, the cigarette paper placed around it and sealed and the product then cut to a predetermined length to produce cigarettes. The completed cigarettes at the outlet of the cigarette making machine are fed across the front of the machine on a belt where they are inspected and placed in containers to be carried to the packaging machines.

In the manufacture of tipped cigarettes, the tipping material of double the size of the tip is placed on the cigarette before severing at intervals equal to the length of two cigarettes. The cigarette is then severed both at a point intermediate of adjacent sections of the tipping material and in the middle of each section of the tipping material. As a result, the tipped cigarettes are delivered from the cigarette making machine with alternate cigarettes reversed, that is, the tip on one cigarette is at the forward end and the tip on the next cigarette is at the rear end. Heretofore, it has been the practice to provide two transverse belts to deliver the cigarettes across the front of the machine for inspection. Suitable means are provided for feeding each alternate cigarette to the inner belt and the next cigarette is fed to the outer belt. This results in the cigarettes traveling along the transverse belts to the operator or inspector in reversed positions. In removing the cigarettes, it is thus necessary for the operator to reverse those taken from one of the belts before placing them in the container so that the cigarettes will be delivered to the packaging machine with the tips of all of the cigarettes at the same end.

In the present invention I provide means for turning the cigarettes delivered to one of the transverse belts so that all of the cigarettes pass the operator with the tips in the same relative position thereby avoiding the necessity of turning the cigarettes taken from one of the belts. To accomplish this, I deliver each alternate cigarette to the inner belt as heretofore. The alternate cigarettes are delivered to a reversing mechanism comprising two series of radially disposed rotating arms. These arms are arranged on a platform or table provided with circular guide walls so that the cigarette is conveyed about the

center of each set of arms. The first set of arms carry the cigarette through a path of substantially 270° whence it falls to a lower level at the point where the second set of arms is arranged. The second set of arms rotates in a reverse direction and again carry the cigarette through a path of substantially 90° whence it passes through an opening to the second belt. In this travel the position of the tip of the cigarette has been reversed so that the cigarettes on the two transverse belts are then arranged with their tips at the same end.

In the accompanying drawings I have shown one embodiment of the invention. In this showing:

Fig. 1 is a plan view;

Fig. 2 is a vertical, sectional view on line 2—2 of Fig. 1;

Fig. 3 is a similar view on line 3—3 of Fig. 1; and

Fig. 4 is a detailed, vertical, sectional view on line 4—4 of Fig. 1.

Referring to the drawings, the reference numeral 1 designates a belt by means of which the formed and severed cigarettes are delivered from the cigarette making machine (not shown). As is well known, the cigarette passes to the belt 1 from the tube of the cigarette making machine past a cutter (not shown) which severs the tubular cigarette body at proper intervals to deliver cigarettes of the desired length. The belt 1 passes over pulleys (not shown) one of which is driven in any suitable manner. In manufacturing tipped cigarettes, the tipping material of double length is placed on the paper at intervals equal to the length of two cigarettes. A cutter severs the tubular body at a point intermediate between two strips of tipping material and also at the center of the tipping material so that, as the cigarettes emerge from the cigarette making machine, the position of the tips is reversed. The cigarette may be conveyed across the front of the machine over a table (not shown) on belts 2 and 3. It has heretofore been customary to provide a device for removing each alternate cigarette from the belt 1 to the belts 2 and 3. One of such devices is shown in alignment with the belt 2. As shown (see Fig. 2) it consists of a hub 4 having a plurality of arms or blades 5. The hub is mounted on a suitable shaft 6 which is driven in any suitable manner. The speed of rotation is such that one of the arms 5 passes transversely over the belt as each alternate cigarette moves along the belt 1 to deliver it to the belt 2. A plurality of such cigarettes C is shown

on belt 2 with the tips T inwardly or away from the front of the table.

If the alternate cigarette were delivered to the belt 3 by a similar device, the tip would be reversed. To provide mechanism for turning the cigarette, I deliver it to a table or platform 7. A plurality of radial arms 8 are rotatably mounted over this table. As shown, these arms are carried by a shaft 9. This shaft is supported in suitable bearings 10 carried by a bearing plate 11. Shaft 9 is provided with a bevel gear 12 meshing with a bevel pinion 13 on the shaft 6. The portion of the table over which the cigarettes are conveyed by the radial arms 8 is surrounded by a circular wall or flange 14. As shown in Fig. 1, the center of the turning device is substantially in alignment with the belt 1. As each alternate cigarette passes along the belt, it is engaged by one of the radial arms 8. The wall 14 prevents displacement of the cigarette and the cigarette is conveyed over the table 7 through a path of substantially 270°. At this point the table 7 terminates and a second table 15 is arranged beneath it. The second table is likewise surrounded by a wall or flange 16 to form a guide for the cigarettes. A shaft 17 is arranged centrally of the lower table, this shaft being supported in suitable bearings 18 which are also carried by the bearing plate 11. The shafts 9 and 17 are provided with spur gears 19 to rotate the shaft 17 in the opposite direction from the direction of rotation of the shaft 9. Shaft 17 also carries a plurality of radial arms 20.

When the cigarette passes on to the table 15, one of the arms 20 then carries it through a path of approximately 90° to a point where it is over the belt 4. At that point, the plate or table is provided with an opening 21 through which the cigarette falls on to the belt 3. As the alternate cigarettes delivered to the table 7 were arranged with the tips toward the center, when they pass on to the table 15, the tips are at the outer edge toward the flange 16. Thus, as the cigarettes pass through the opening 21 to the belt 3, the tips are arranged inwardly as indicated and are thus similarly arranged to the cigarettes on the belt 2. When the cigarettes reach the table (not shown) where the operator or inspector removes them and places them in containers to be carried to the packaging machines, it is therefore not necessary to reverse the cigarettes from one of the belts.

At the point where the cigarettes pass from the table 15 to the belt 3, an adjusting plate 22 may be provided. This plate may be slidably mounted at the edge of the table 15 (see Fig. 4) to permit desired adjustment to properly place the cigarette on the belt 3.

I claim:

1. A device of the character described comprising a belt to deliver cigarettes from a cigarette making machine, a pair of belts traveling at right angles to the first belt, means for delivering alternate cigarettes to one of said pair of belts, a platform in alignment with the first belt, a radially disposed rotating arm on the platform to

propel the alternate cigarette through an arc, a second platform at a lower elevation than the first platform, a radially disposed rotating arm on the second platform rotating in the opposite direction from the first mentioned arm, a portion of its path being beneath the path of the first arm, and means for delivering a cigarette from the second platform to the second of the pair of belts.

5 10 15 20 25 30 35 40 45 50 55 60

2. A device of the character described comprising a belt to deliver cigarettes from a cigarette making machine, a pair of belts traveling at right angles to the first belt, means for delivering alternate cigarettes to one of said pair of belts, a platform in alignment with the first belt, a radially disposed rotating arm on the platform to propel the alternate cigarette through an arc, a second platform at a lower elevation than the first platform, a radially disposed rotating arm on the second platform rotating in the opposite direction from the first mentioned arm, a portion of its path being beneath the path of the first arm, means for delivering a cigarette from the second platform to the second of the pair of belts, and a guide wall surrounding each platform.

3. A device of the character described comprising a belt to deliver cigarettes from a cigarette making machine, a pair of belts traveling at right angles to the first belt, means for delivering alternate cigarettes to one of said pair of belts, a platform in alignment with the first belt, a radially disposed rotating arm on the platform to propel the alternate cigarette through an arc, a second platform at a lower elevation than the first platform, a radially disposed rotating arm on the second platform rotating in the opposite direction from the first mentioned arm, a portion of its path being beneath the path of the first arm, a portion of the second platform extending over the second of the pair of belts and being provided with an opening through which a cigarette propelled by the rotating arm passes on to the second of the pair of belts.

4. A device of the character described comprising a belt to deliver cigarettes from a cigarette making machine, a pair of belts traveling at right angles to the first belt, means for delivering alternate cigarettes to one of said pair of belts, a platform in alignment with the first belt, a radially disposed rotating arm on the platform to propel the alternate cigarette through an arc, a second platform at a lower elevation than the first platform, a radially disposed rotating arm on the second platform rotating in the opposite direction from the first mentioned arm, a portion of its path being beneath the path of the first arm, a portion of the second platform extending over the second of the pair of belts and being provided with an opening through which a cigarette propelled by the rotating arm passes on to the second of the pair of belts, and a guide wall surrounding each platform.

JOHN T. DALTON.
